CONTINUOUS-TYPE SPAGHETTI DRIER

Charles Hummel, Uzwil, Switzerland, assignor to
Gebriider Buhler, Uzwil, SwitzerlandApplication April 28, 1949, Serial No. 90,225
In Switzerland November 22, 1948

1 Claim. (Cl. 34—205)

1

My present invention relates to a mechanical arrangement for continuously drying spaghetti, the term "spaghetti" in this connection and in the following description also including macaroni, noodles and like foodstuff articles made of doughy paste.

Spaghetti are made of a dough comprising semola and water, contain approximately 30% water upon extrusion and, therefore will not keep. In order to render them storable, their water contents must be lowered by drying to approximately 13%. To such end, drying cabinets have been used, in which the suspended spaghetti are slowly dried in heated air.

Such conventional drying cabinets, however, are two bulky and require considerable manual handling in charging and discharging. Further, the drying operation in these cabinets is relatively difficult and requires considerable attention and care from the part of the operatives, since such operation has to be adapted not only to the articles to be dried, but also to the prevailing atmospheric conditions.

Thus, there exists a substantial need for effecting such drying operation in a purely mechanical way and manner in order to eliminate the manual handling of the spaghetti.

To such end, the drier according to my present invention comprises an automatic hanging device having an endless chain and a plurality of spaced rods secured to said chain for receiving the spaghetti issuing from the dough extrusion press, a drying compartment having at least one pair of drying-chains by means of which the said rods with the hanging spaghetti are moved in succession through the said compartment, transport means adapted to payout the said spaghetti-dressed rods from the said hanging device on to said drying-chains, and further transport means adapted to deliver the said rods after having passed through the said compartment on to a delivery chain.

The said compartment suitably is provided with a plurality of superjacent drying-chains and is subdivided into chambers extending transversely of the direction of movement of the said chains; each said chamber being provided with a fan and heating means for producing optimal conditions for drying in the respective chamber.

One form of my present invention is shown, by way of example, in the accompanying drawing, in which—

Fig. 1 shows a schematical longitudinal section through the entire arrangement.

Fig. 2, in a larger scale, a vertical section on the line II—II of Fig. 1.

2

Fig. 3 a vertical longitudinal section through the delivery side of the arrangement,

Fig. 4 a vertical cross-section on the line IV—IV of Fig. 3,

Fig. 5 a horizontal section on the line V—V of Fig. 4,

Figs. 6—8 show a cutting-mechanism associated with the hanging device, in a side view, top plan view and perspective view respectively, and

10 Figs. 9 and 10 in plan and vertical section on the line X—X of Fig. 9 respectively and in larger scale, the cutting-mechanism disposed below the extrusion dies of the dough press.

The spaghetti are extruded in the form of 15 strings 2 through dies 1. The hanger device A serves for mounting or suspending the extruded spaghetti strings astride of rods 6, and comprises two endless conveyer chains 4 provided with spaced bracket means 5 for the ends 20 of the rods 6. The bracket means 5 are pivoted to the said chains 4 and weighted so that—irrespective of whether the said chains 4 run in a vertical or horizontal direction—they always assume such a position that their recessed bearing portions 7 for receiving the said rods 6 are situated on top. Each chain 4 is so guided through sprocket wheels 8 that each rod 6 entering into the hanger A on the horizontal stretch 4a of the chain 4 hits against the extruding spaghetti strings approximately at midlength thereof. The extruding spaghetti strings, therefore, are taken along by the rods 6, adhering thereto in the moist state. A knife 10 (Figs. 9, 10) now enters into operation, cutting the spaghetti strings below the dies 1, whereupon the cut-off portions drop to 30 constitute the second legs of the spaghetti which now hang in U-form from the rod.

As shown in Figs. 9 and 10, the said knife 10 is secured to a slide 11 guided in a rail 12 which 40 also forms a bracket for the dies 1. The slide 11 is secured to an endless chain 13 running over the sprocket wheels 14 and driven through an electric motor 15. In order to ensure that the extruding spaghetti strings 2 are cut approximately to equal lengths, the movement of the knife 10 has to be synchronized to the speed of delivery of the extruding spaghetti and, further, to relate the operating speed of the conveyer chains 4 to that of the knife 10. The said motor 50 15 is thrown on by a sprocket wheel 8 of the conveyer chain 4, the circumference of wheel 8 corresponding to the distance between two consecutive rods 6 on the said chain. An arm 16 is secured to the hub of said sprocket wheel 8 and operates a switch 17 and, thus, a relay 18 at each revolution of the wheel 8. The knife 10 is quickly

run underneath and along the die and severs the spaghetti strings 2, whereupon it returns on the chain 13 into its initial position. The motor 15 is positively thrown out by means of the worm-gear 19, 20 mounted on the motor and comprising a cam 21 which actuates the cut-out 22 and, thus, the said relay 18. The transmission ratio of the said worm gear is so chosen that the worm wheel 20 performs one revolution for each revolution of the chain 13. The speed of extrusion of the spaghetti may be regulated by varying the rotary speed of the worm which press the dough through the extrusion press.

As seen in Fig. 1, the horizontal stretch 4a of the conveyer chains 4 is followed by a vertical stretch 4b on which the rods 6 are raised through a distance which approximately corresponds to the length of the depending legs of the U-shaped spaghetti strings mounted on the said rods.

In the following horizontal stretch 4c of the chains 4, the lower ends of the suspended spaghetti strings arrive within the range of a second cutting device including a knife 23 for cutting the spaghetti to uniform length. Such second cutting device is shown in Figs. 6-8. The spaghetti end-portions are caught in a rack 24, and the knife 23 slides along the underside of the latter. The knife 23 is secured to a slide 24 in a manner similar to that described above in connection with the knife 10, which slide is moved along the rack 24 on a guideway 27 through an endless chain 25 and sprocket wheels 26. One of the said sprocket wheels 26 is driven continuously through a motor 28.

The waste portions cut off the spaghetti ends, drop into a hopper 9 from which they are transported on a band 9' to a point where they are cut up and returned into the mixing or kneading trough of the dough-press.

The loaded rods 6 thence are moved further onward in the vertical portion 4d of chain 4 and over the sprocket 29, and downward in the other vertical portion 4e of chain 4. During such downward movement, the rods 6 are lifted from the bracket means 5, through lifting and conveying means, and delivered to drier chains.

The drier B comprises three pairs 30, 31 and 32 of drier chains disposed above each other and endlessly moving horizontally over sprockets 33. The said drier chains comprise links 34 which are notched at 35 to form bearings for the end portions of the rods 6. The latter are slowly passed through the drier B and the moisture contents of the spaghetti thus reduced. For such purpose, the drier is subdivided, transversely to the direction of movement of the drier chains, in a number of compartments of which three, viz. 36-38, are shown in the drawing. Each compartment defined by walls, comprises a fan 39 (Fig. 2) and heating means such as for instance electric heating rods 40 disposed above each drier chain. The drying air is circulated, through the fan 39 which is driven from a motor 41, in the sense of the arrow line indicated in Fig. 2 by dash-and-dot, being heated by the heating means 40. Fresh air is sucked in through an adjustable clack valve 42 disposed in the suction space of the fan, and a corresponding portion of spent or moisture-laden air may escape through an adjustable clack valve 43 disposed in the pressure space of the fan. As may be seen from Fig. 2, the dry air sweeps the spaghetti longitudinally so as to cause a good drying action. The state of the circulated drying air may be adapted to the most favorable drying conditions in each compartment. The speed of the cycled air may be regulated by regulating

the speed of the fan. The temperature and humidity of the cycled air may be adapted to the desired conditions in each compartment by regulating the heating means and by adjusting the clack valves 42 and 43. The drier B also may comprise more than three compartments, according to the performance desired of the drying arrangement, and at the outlet end of the drier one or two compartments may be provided which operate without heating and with open valves, i. e. with fresh air, in order to cool the spaghetti in these latter compartments down to the outside temperature before leaving the drier B.

The rods loaded with the dried spaghetti are lifted from the links 34 of the drier chains through conveying means and inserted in the bracket means 5 of the upwardly moving portion 4f of conveyer chain 4. The loaded rods then are inserted, through the downwardly moving portion 4g of chain 4, in the links 44 of a pair of delivery chains 45, and fed by the latter to a point where the rods are taken from the chains 45 and freed from the dried spaghetti. The cleared rods 6 are inserted in the empty bracket means 5 underneath the delivery chain 45, whence they are returned through the horizontal portion 4h of conveyer chain 4 back to the hanging device A (Fig. 1), and thus pass through a closed circuit.

The conveyer means for delivering the rods loaded with the damp spaghetti strings, from the chain 4 onto the drier chains 30-32, and the means for lifting the rods loaded with the dried spaghetti string from the drier chains and delivering the same to the chain 4, are built alike. The said two means comprise three pairs of arms 46 (Figs. 1 and 4) disposed one above the other, each pair of arms co-acting with one of the three pairs of drier chains 30-32. To the end of each arm 46, a bracket means 47—similar to the bracket means 5 of conveyer chain 4—is pivoted and always held in vertical position through a weight disposed thereon. The arms 46 are secured to shafts 48 which rotate together and thereby accomplish the transport of the loaded rods from the hanging device to the drier and of the loaded rods from the drier to the conveyer chain 4, and through the latter, to the delivery chain 45.

The speeds of conveyer 4, arms 46, drier chains 30-32 and of the delivery chain 45 have to be tuned to each other so that the arms 46 make a revolution when the drier chains have been advanced through the distance between two teeth, and the delivery chain has to move through the distance between two teeth when the conveyer chain 4 has moved through the distance between two rod brackets 5.

The entire mechanism is driven through an electric motor 4 (Figs. 3 and 5) provided with a reducing gear, a screw wheel 51 and a worm 52 being mounted on the motor shaft 50. The screw wheel 51 drives a screw wheel 53 which meshes with a screw wheel 54 pinned to a vertical shaft 55. A further screw wheel 56 is pinned to the upper end of shaft 55 and meshes with a screw wheel 57 through which one of the sprockets 58 of conveyer chain 4 is actuated. Three further screw wheels 59 are pinned to vertical shaft 55 and mesh with screw wheels 60 on the shafts 48 of the arms 46 to rotate the latter about the shafts 48. As shown in Fig. 4, the said vertical shafts 55 with their screw-wheel drives are provided on each side of the drier. The worm 52 of shaft 50 drives a worm wheel 61 which drives

the sprocket 44 of drier chain 32 through a twin reducing gear comprising the spur wheels 62—65. From spur wheel 65 of drier chain 32 are driven the spur wheels 65 and sprockets 33 of the drier chains 31 and 30 through the intermediate wheels 66. These gear trains also are provided on both sides of the drier and interconnected through a shaft 72, as may be seen from Fig. 4. Further, a screw wheel 67 is pinned to vertical shaft 55 and drives the sprockets 71 of delivery chain 45 through a screw wheel 68 and a reducing gear 69, 70, similar gear trains again being arranged on both sides of the drier and interconnected by a shaft 73.

As described above, the mounting of the dough strings onto the rods, the transport of the loaded rods on the drier chains, the passage of the loaded rods through the drier, the lifting of the rods loaded with the drier goods from the drier chains, and the delivery thereof to a delivery chain are done entirely automatically. Such an arrangement is distinguished by a very high drying performance, requiring a minimal number of attendants.

What I claim as new and desire to secure by Letters Patent is:

In a continuous type drying apparatus for spaghetti to be extruded from a dough press having a plurality of linearly arranged extrusion dies, the combination of a drying compartment, endless drier chains for conveying the spaghetti to be dried through said compartment from a receiving station to a delivery station, endless conveyor

chains passing underneath said extrusion dies and into proximity with said receiving and delivery stations, a plurality of spaghetti receiving rods loosely carried in successive spaced relationship by said endless conveyor chains and arranged to be loaded by spaghetti strings when passing underneath said extrusion dies, means actuated in response to the travelling speed of said rod carrying conveyor chains and to the distance between successive rods for cutting off the extruded spaghetti strings into predetermined lengths for automatically loading successive rods with spaghetti strings, means at said receiving station for transferring the loaded rods to said drier chains, means at said delivery station for transferring the loaded rods from the drier chains again to said endless conveyor chains, and means for discharging the loaded rods from said endless conveyor chains.

CHARLES HUMMEL.
